UNITED STATES PATENT OFFICE

132,944

DESIGN FOR A SOFA OR SIMILAR ARTICLE

Lorin Jackson, New York, N. Y., assignor to Grosfeld House, Inc., New York, N. Y., a corporation of New York

Application April 2, 1942, Serial No. 106,436

Term of patent 3½ years

To all whom it may concern:

Be it known that I, Lorin Jackson, a citizen of the United States of America, residing in New York city, county of New York, and State of New York, have invented a new, original, and ornamental Design for a Sofa or Similar Article, of which the following is a specification, reference being had to the accompanying drawing, forming part thereof, wherein:

Figure 1 is a front perspective view of a sofa or similar article, showing my new design, a portion of the tassels being omitted to show the leg; and

I claim:

The ornamental design for a sofa or similar article, substantially as shown and described.

LORIN JACKSON.
